UNITED STATES PATENT OFFICE.

EDWARD M. ATKINSON, OF PORTLAND, OREGON.

FLEXIBLE HANDLE FOR CONTAINERS.

Application filed February 18, 1925. Serial No. 10,053.

To all whom it may concern:

Be it known that I, EDWARD M. ATKINSON, a citizen of the United States, residing in Portland, county of Multnomah and State of Oregon (and whose address is post-office box 159, in said Portland), have invented a new and useful Improvement in Flexible Handles for Containers, of which the following is a specification.

This invention relates to an improved type of handles for cans, bottles or other containers, and is so constructed as to be adaptable to many shapes, and readily-attached or detached. This is done by the use of small size iron wire. Other handles or bails are oftentimes made of tension or spring wire, and are unnecessarily rigid. Such material is hard and slow to manipulate. Machines for that purpose are costly, and bending of tension wire to order is refused by large factories. My improvement can be made with hand nippers and a punch, or by simple machines to work the soft wire. Production can thus be carried on cheaply over a wide section by amateurs. Material used is preferably small size galvanized wire and waste pieces of thin galvanized iron. The wire is straightened by stretching and is rubbed with emery cloth while in these long lengths to polish it for a finish. Tumbling quickly removes cutting ends of this soft round and flat metal.

Economy is gained by using only four coils in connection with three bends of the wires, as these give all the strength needed in locking the handle on containers. These coils can easily be increased or lessened to fit the wire snugly to containers. Durability is secured by a simple means of attaching or detaching the device, which is by one motion for each, like a hook and eye. The flat metal of the handle provides space for notices or advertising.

This cheapened construction permits low prices, which will increase sales.

Fig. I is a side view of my improved flexible handle attached to a milk bottle.

Fig. II shows the flat metal part of the handle held in position.

Fig. III is a side view of the top part of the flexible handle, showing how it is fastened to the wire, encircling bottles, etc.

Fig. IV shows my improved flexible handle detached from milk bottle.

In these figures, 1 is a bottle, 2 the top

part of the handle, of which 3 is the wire passed through holes 6, 6 in the flat metal 4, and joined to wire 7 by a coil 12 at its depression 11 to center it in the encircling wire 7. 5, 5 are folds in the cut off corners of the flat metal 4 which prevent its rolling on wire 3 by being bent against it.

The angular shape of wire 3 shown in Figs. I and IV with its end 13 passed through coils 9 and 10 of the encircling wire 7 and through coil 8 of wire 3, is the locking device. The handle is detached from a bottle by unhooking the end 13 from its coil 8; which motion also moves wire 3 backward through coil 10. This allows enough slack to pass the handle over the neck of bottles, or to disengage it from other containers.

The various angular bends made in wire 3 hold it securely in place in the coils. The operation just described does not materially change these shapes nor will it break the wire. It is evident that this type of handle can be used on many shapes of containers, and if necessary can be lengthened by splicing to encircle several packages.

I claim:

1. A flexible handle for containers and made of two pieces of small size iron wire, one about three-quarters the length of the other and terminating in coils, which wire is encircled at a depression midway of the coiled ends by the coiled end of the longer wire, which also has a second coil, but formed distant enough from its tip to allow this wire end to pass through it after going through coils at the ends of the shorter wire, and drawn taut so as to have about the shape of an equilateral triangle.

2. A flexible handle for containers and made of two pieces of small size iron wire, one about three-quarters the length of the other and terminating in coils, and encircled at a depression midway by the coiled end of the longer wire, which also has a second coil, but formed distant enough from its tip to allow this wire end to pass through it after going through coils at the ends of the short wire and drawn taut so as to have about the shape of an equilateral triangle.

3. A flexible handle for containers and made of two pieces of small size iron wire, one about three-quarters the length of the other and terminating in coils, and encircled at a depression midway by the coiled end of the longer wire, which also has a second coil, but formed distant enough from its tip to allow this wire end to pass through it after going through coils at the ends of the short wire and drawn taut so as to have about the shape of an equilateral triangle; the longer wire having a piece of flat metal threaded thereon between its coils; the cut off corners of such flat metal being pressed against this longer wire.

EDWARD M. ATKINSON.
